(57) **ABSTRACT**

The invention relates to a multibeam antenna for emitting/receiving a radiofrequency signal in a plurality of directions in at least one frequency band, the antenna including: a floorplan (P); a dielectric substrate (11) having a permittivity (ϵ_1), the substrate (11) being arranged on the floorplan (P); and a plurality of assemblies (E_i) of antenna elements arranged on the substrate (11), each assembly (E_i) corresponding to a direction of the antenna. The antenna according to the invention is characterized in that said antenna also includes a dielectric superstrate (12), having a higher permittivity (ϵ_2) than the permittivity (ϵ_1) of the substrate (11), arranged on the assemblies (E_i) of antenna elements, and in that the assemblies (E_i) are interleaved one under the other so as to form a column, the assemblies (E_i) corresponding to a single antenna direction being separated by a number of assemblies equal to the number of antenna directions.

CROSS-REFERENCE TO RELATED
APPLICATIONS

The present application is a non-provisional application claiming the benefit of International Application Number PCT/EP2010/056416, filed May 11, 2010, which claims priority under 35 USC 119 to French Patent Application Number 0953086, filed May 11, 2009, which are incorporated herein by reference in their entirety.

GENERAL TECHNICAL FIELD

The invention relates to the field of monofrequency of 15 multifrequency multibeam antenna for emitting/receiving a radiofrequency signal in a plurality of directions.

STATE OF THE PRIOR ART

Obtaining one or more beams from directive antenna takes place to the detriment of the size of the antenna.

Indeed, the more the antenna has to be directive (in other words the more it is wished to have an antenna that can radiate in one favoured direction or several directions and has to have several independent beams) the greater must be its radiating surface area.

FIG. 1 illustrates a multibeam antenna of known type.

This antenna, constituted of three panels P_1 , P_2 , P_3 , can 30 operate in three directive beams.

This antenna—see FIG. 2—comprises a ground plane P and a dielectric substrate 11 , having a dielectric constant ϵ_1 . The substrate 11 is arranged on the ground plane P .

The antenna further comprises a plurality of assemblies E_i of antenna elements, said antenna elements S_{ij} are arranged 35 on the substrate 11 (i corresponds to the number of the assembly and j to the number of the antenna element in the assembly i).

The antenna elements S_{ij} are suited to emitting/receiving a 40 radiofrequency signal in a given direction so that each assembly E_i is associated with a direction of the antenna. It is considered that the antenna emits/receives the signal in one or more frequency bands in different directions, defined by each panel.

FIG. 2 illustrates in a schematic manner an assembly E_1 of 45 antenna elements S_{ij} .

The elements S_{ij} are supplied according to a distribution law (a_{ij}, ϕ_{ij}) , a_{ij} being the amplitude of the emitted or received signal and ϕ_{ij} its phase. This law is applied to each group of 50 assemblies i (formed of antenna elements j) of the same panel with the aim of forming a coherent radiation pattern and favouring a determined direction A_1, A_2, A_3 , normally a given azimuth in the horizontal plane. In its most simple form, the elements E_i are supplied in series or in arborescence.

FIGS. 3a and 3b illustrate respectively a top view and a side view of the ground plane P with the substrate 11 and an antenna element S_{i1} used in antennas of known type.

In multibeam antennas of this type (see FIG. 1), the assemblies corresponding to a single direction are arranged in several columns, typically up to four columns. The columns are moreover arranged side by side.

A problem is that such an arrangement is bulky, particularly with a view to having more and more directive antennas, in other words that can radiate in several directions. Indeed, it would be necessary to add columns.

2
DESCRIPTION OF THE INVENTION

The invention makes it possible to have a multibeam antenna of reduced size compared to known antenna solutions 5 of the same type.

According to a first aspect, the invention relates to a multibeam antenna for emitting/receiving a radiofrequency signal in a plurality of directions in at least one frequency band, the antenna comprising: a ground plane; a dielectric substrate, having a permittivity, the substrate being arranged on the ground plane; a plurality of assemblies of antenna elements arranged on the substrate, each assembly corresponding to a direction of the antenna.

The antenna according to the invention is characterised in 15 that it further comprises a dielectric superstrate, having a permittivity greater than the permittivity of the substrate, arranged on the assemblies of antenna elements, and in that the assemblies are interleaved one under the other so as to 20 form a column, the assemblies corresponding to a single antenna direction being separated by a number of assemblies equal to the number of antenna directions.

The antenna according to the invention may moreover exhibit one or more of the following characteristics:

the antenna elements of a single assembly are spaced apart by a distance less than a wavelength λ , the wavelength λ corresponding in the monofrequency case to the frequency at which the antenna has to operate and in the multifrequencies case to the central frequency defined by $(f_{max} - f_{min})/2$ where f_{max} is the maximum frequency at which the antenna has to operate and f_{min} is the minimum frequency at which the antenna has to operate; the antenna elements belonging to different assemblies are spaced apart by a distance less than λ/n , where X correspond to: in the monofrequency case, to the frequency at which the antenna has to operate; in the multifrequencies case, to the central frequency defined by $(f_{max} - f_{min})/2$ where f_{max} is the maximum frequency at which the antenna has to operate and f_{min} is the minimum frequency at which the antenna has to operate; and where n is the number of different assemblies (E_i); for each direction of the antenna an identical number of assemblies of antenna elements; the assemblies corresponding to a single antenna direction are connected in series or in arborescence; each assembly comprises an identical number of antenna elements; the antenna elements are square, equilateral triangle shaped or ellipsoidal shaped patches; each side of each element is of dimension equal to

$$a \frac{\lambda_0}{4\sqrt{\epsilon_1 + \delta\epsilon_2}}$$

where ϵ_1 is the permittivity of the substrate and ϵ_2 is the 55 permittivity of the superstrate, λ_0 is the wavelength corresponding to the frequency associated with the antenna element, the value σ is approximately equal to: $\sigma = h_1/(h_1 + d)$;

the antenna elements are orthogonal double polarisation patches having two independent accesses making it possible to achieve diversity of polarisation.

The antenna according to the invention is monofrequency or multifrequency and in each frequency band it is possible to have several beam directions.

According to a second aspect, the invention relates to a cellular communication network comprising an antenna according to the first aspect of the invention.

DESCRIPTION OF DRAWINGS

Other characteristics and advantages of the invention will become clearer on reading the description that follows, which is purely illustrative and non limiting and should be read with reference to the appended drawings in which, apart from FIGS. 1, 2, 3a and 3b already discussed:

FIG. 4 illustrates a multibeam antenna according to the invention;

FIGS. 5a and 5b illustrate respectively a top view and a side view of the ground plane with a dielectric substrate and superstrate and an antenna element of the antenna of the invention;

FIGS. 6a and 6b illustrate respectively a square patch and an equilateral triangle shaped patch implemented in the antenna of the invention;

FIG. 7 illustrates an antenna with three monofrequency beams according to the invention;

FIG. 8 illustrates an arrangement of antenna elements in an assembly for a bifrequency antenna according to the invention;

FIG. 9 illustrates the variation of the coupling between two assemblies of antenna elements as a function of the distance between the elements for the elements of an antenna of known type and for smaller elements, implemented in an antenna of the invention, having identical radiation characteristics;

FIG. 10 illustrates the performances in terms of isotropic gain of the antenna elements of an antenna of known type and for an antenna with smaller elements implemented in an antenna of the invention, having identical radiation characteristics;

FIGS. 11a and 11b illustrate the reduction in size from a dipole into a monopole used in the antenna of the invention;

FIG. 12 illustrates a side view of the ground plane with a dielectric substrate and superstrate and an antenna element of the antenna of the invention to explain the dimensions of the antenna element.

DETAILED DESCRIPTION OF THE INVENTION

Structure of the Antenna

FIG. 4 illustrates a multibeam antenna having a reduced size compared to multibeam antenna of known type (see antenna of FIG. 1).

FIGS. 5a and 5b illustrate, respectively, a top view and side view of the ground plane P with the substrate 11, the superstrate 12 and an antenna element S_{ij}.

This antenna comprises a ground plane P, a dielectric substrate 11 having a dielectric constant ϵ_1 arranged on the ground plane P and a plurality of assemblies E_i of antenna elements S_{ij} arranged on the substrate 11.

As already mentioned, each assembly E_i corresponds to a direction of the antenna.

To reduce the size of the antenna, the assemblies E_i of antenna elements S_{ij} are interleaved one under the other so as to form a column and the assemblies E_i which correspond to a single antenna direction are separated by a number of assemblies equal to the number of directions of the antenna.

In other words, a single direction of antenna is found on the column of assemblies of antenna elements in a periodic manner, the period being equal to the number of direction of the antenna.

Such an interleaving can generate a coupling between the antenna elements which are closer than in antennas of known type.

To avoid the coupling between the antenna elements, the size of the antenna elements is reduced.

This reduction in size is possible by the fact that the antenna comprises a dielectric superstrate 12 having a permittivity ϵ_2 greater than the permittivity ϵ_1 of the dielectric substrate 11.

10 The use of this superstrate 12 makes it possible to conserve radiation characteristics identical to an antenna element of larger size.

Moreover, a resistance R is connected between the ground plane P and each antenna element S_{ij}. The resistance R is typically equal to one Ohm. This resistance R serves to short-circuit one of the radiating sides of the antenna element. This short-circuit serves to transform the radiating element of size $\lambda/2$, constituted of two monopoles, each of size $\lambda/4$ of each side of the dipole, into a single monopole of size $\lambda/4$ and consequently makes it possible to divide by two the electrical dimensions of the radiating element (see FIG. 11).

Said resistance R also makes it possible to increase substantially the pass band of the antenna in its resonating behaviour.

25 In order to obtain good performances for each direction of the antenna, the assemblies E_i which correspond to a single direction of antenna are connected together in series.

The antenna elements belonging to different assemblies are spaced apart by a distance less than λ/n , where λ corresponds:

35 in the monofrequency case, to the frequency at which the antenna has to operate;

in the multifrequencies case, to the central frequency defined by $(f_{max} - f_{min})/2$ where f_{max} is the maximum frequency at which the antenna has to operate and f_{min} is the minimum frequency at which the antenna has to operate; and where

n is the number of different assemblies (E_i).

Typically a spacing less than $0.9\lambda/n$ will be taken.

40 The antenna elements of a single assembly are for their part spaced apart by a distance less than λ .

The spacing constraints make it possible to obtain a radiation pattern of the different elements with a single main lobe in an angular aperture (-90° , $+90^\circ$) of the plane of the assembly 45 with respect to the main radiation axis perpendicular to the assembly.

Beyond this spacing, additional main lobes appear at each end of the angular aperture (-90° , $+90^\circ$) degrading the directivity performances of the assembly.

50 Monofrequency Case

In FIG. 7 is illustrated an antenna with three monofrequency beams A, B, C. In this figure, in each assembly E₁, E₂, E₃ the antenna elements S_{ij} are connected together.

Furthermore, all of the assemblies E₁ are connected to 55 obtain a first beam A, all of the assemblies E₂ are connected to obtain a second beam B and all of the assemblies E₃ are connected to obtain a third beam C.

The antenna elements of a single assembly are separated by a distance of 0.5λ and the antenna elements of different 60 assemblies are separated by a distance of 0.3λ (there are three different beams).

Compared to antennas of known type using a single beam, the use of several beams (particularly the use of a single UMTS carrier with a different scrambling code per beam) 65 makes use of independent and physically similar antennas having radiation patterns with different azimuths in the horizontal plane.

This approach entails an increase in the overall surface of the antenna solution, comprising a plurality of specific antennas.

Multifrequencies Case

In FIG. 8 is illustrated the arrangement of antenna elements S_{ij} in an assembly E_i for a bifrequency antenna. The number of antenna elements S_{ij} is doubled compared to a monofrequency antenna (see FIG. 7).

Compared to antennas of known type, the use of several close frequencies for different telecommunications standards (particularly the use of the spectrum 880-960 MHz for GSM and UMTS) makes use of independent and physically similar antennas having the same radiation pattern.

This approach entails an increase in the overall surface of the antenna solution, comprising a plurality of specific antennas.

Antenna Elements S_{ij}

The antenna elements S_{ij} are preferably square or equilateral triangle shaped patches of sides of dimension d :

$$d = \frac{\lambda_0}{4\sqrt{\epsilon_1 + \delta\epsilon_2}}$$

where ϵ_1 is the dielectric constant of the substrate and ϵ_2 is the dielectric constant of the superstrate, λ_0 is the wavelength in a vacuum, δ is the partial contribution of the dielectric ϵ_2 in the radiation of the cavity of the radiating element.

This radiation operates in effective dimensions taking into account the physical dimension d of the element and an overflow of the fields, which extend over a distance approximately the value of the thickness h_1 of the substrate (see FIG. 12). It may be noted that the value δ is approximately equal to:

$$\delta = \frac{h_1}{h_1 + d}.$$

FIGS. 6a and 6b illustrate respectively a square patch and an equilateral triangle shaped patch, each side is of dimension d (see above).

Thanks to the reduction in the dimensions of the antenna elements S_{ij} , the interleaving of the assemblies E_i is possible and the size obtained is identical to the size necessary for a single direction of the antenna of known type (see the comparison between the configuration of FIG. 1 and the configuration of FIG. 4).

Performances

FIG. 9 illustrates the coupling between two assemblies of antenna elements as a function of the distance between the elements for the elements of the antenna of known type (curve 20) and for the smaller elements (curve 30) having identical radiation characteristics. To ensure good operation between different systems, it is aimed to obtain a coupling between different antennas less than -30 dB.

With a typical distance of 0.4λ between the antenna elements, the two antennas of known type have a coupling between each other of around -10 dB whereas with the same spacing, the two antennas with the smaller antenna elements have a coupling less than -50 dB between them.

FIG. 10 illustrates the performances in terms of isotropic gain of the antenna elements of the antenna of known type (curve 40) and for the antenna with smaller elements (curve 50).

It is observed that, despite the addition of the superstrate and the substantial reduction in the physical dimensions of

the compact radiating element, its gain is around 3 dBi at the resonance frequency, scarcely 0.2 dB below the gain of a conventional radiating element (around 3.2 dBi).

The invention claimed is:

1. Multibeam antenna for emitting/receiving a radiofrequency signal in a plurality of directions in at least one band of frequencies, the antenna comprising:

a ground plane (P);

a dielectric substrate (11), having a permittivity ϵ_1 , the substrate (11) being arranged on the ground plane (P); a plurality of assemblies of antenna elements arranged on the substrate (11), each assembly corresponding to a direction of the antenna;

wherein the antenna further comprises a dielectric superstrate (12), having a permittivity (ϵ_2) greater than the permittivity (ϵ_1) of the substrate (11), arranged on the assemblies of antenna elements, and in that the assemblies are interleaved one under the other so as to form a column of antenna elements in a periodic manner, the period being equal to the number of direction of the antenna.

2. Antenna according to claim 1, wherein the antenna elements of a single assembly are spaced apart by a distance less than one wavelength λ , the wavelength λ corresponding in the monofrequency case to the frequency at which the antenna has to operate and in the multifrequency case to the central frequency defined by $(f_{max} - f_{min})/2$ where f_{max} is the maximum frequency at which the antenna has to operate and f_{min} is the minimum frequency at which the antenna has to operate.

3. Antenna according to claim 1 or claim 2, wherein the antenna elements belonging to different assemblies are spaced apart by a distance less than λ/n , where λ corresponds to:

in the monofrequency case, the frequency at which the antenna has to operate;

in the multifrequencies case, the central frequency defined by $(f_{max} - f_{min})/2$ where f_{max} is the maximum frequency at which the antenna has to operate and f_{min} is the minimum frequency at which the antenna has to operate; and where

n is the number of different assemblies (E_i).

4. Antenna according to claim 1, comprising for each direction of the antenna an identical number of assemblies of antenna elements.

5. Antenna according to claim 1, wherein the assemblies corresponding to a single antenna direction are connected in series or in arborescence.

6. Antenna according to claim 1, wherein each assembly comprises an identical number of antenna elements.

7. Antenna according to claim 1, wherein the antenna elements are square, equilateral triangle shaped or ellipsoidal shaped patches.

8. Antenna according to claim 1, wherein each side of each antenna element is of dimension equal to

$$\frac{\lambda_0}{4\sqrt{\epsilon_1 + \delta\epsilon_2}}$$

where ϵ_1 is the permittivity of the substrate and ϵ_2 is the permittivity of the superstrate, λ is the wavelength corresponding to the frequency associated with the antenna element, the value δ is approximately equal to: $\delta = h_1/(h_1 + d)$.

9. Antenna according to claim 1, wherein the antenna elements are patches with double orthogonal polarisation having two independent accesses making it possible to achieve diversity of polarisation.

10. Cellular communication network comprising an 5 antenna according to claim 1.
